United States Patent Office.

LEWIS S. WISWELL, OF UTICA, NEW YORK.

Letters Patent No. 78,503, dated June 2, 1868.

IMPROVED MACHINE FOR FASTENING LACING-HOOKS TO GAITERS.

The Schedule referred to in these Letters Patent and making part of the same.

TO ALL WHOM IT MAY CONCERN:

Be it known that I, LEWIS S. WISWELL, of Utica, New York, have invented a new and useful Machine for Fastening Lacing-Hooks and the like to Gaiters and similar work; and I do hereby declare that the following is a full, clear, and exact description of my said invention, and of the mode of operation of the same, reference being had to the annexed drawing, making a part of this specification, in which—

Figure 1 is a side view of the machine,

Figure 2, a front view,

Figure 3, a perspective view of the slides and spring,

Figure 4, a perspective view of the warp, arm, and head of punch, and

Figure 5 a side view of hopper and agitator.

A is the base of the machine.

B, a standard.

B¹ B², arms extending therefrom.

C, lever.

C', friction-roller therein.

D, punch.

D¹, recess in head of punch for holding hook.

D², spring.

E, standard for carrying.

F, the cam-wheel.

F¹, treadle-rod.

F² F³, pins for moving the slides.

G, a slide.

G¹, friction-roller,

G², tapering notch in side.

G³, pin to regulate movement of G.

G⁴, pin by which G is moved by pins F² and F³.

G⁵, pin to move.

H, upper slide.

H¹ H², notches in end of H.

H², spring to control movements of H.

I is the hopper.

I¹, agitator.

I², connecting-rod.

I³, arm, ratchet, and pawl, for turning agitator.

I⁴, ratchet and spring-catch, to prevent agitator from turning back.

K K', ways for conducting hooks from hopper.

L, arm for pushing hook into recess in head of punch.

L', spring for retracting arm.

The base, A, has a standard rising from its centre, which forms the fulcrum or support of the lever C, which lever has a friction-roller, C', running on the cam, while its other end presses down the punch D.

The punch D is sustained by arms B¹ and B², extending from the face of the standard B. It has in its lower end and on the back side, a recess and notch for taking in and holding the head of the hook while being pressed through the work and clinched. A side view of the recess is seen in fig. 1, and a perspective view of a section of the head of the punch through the recess is seen in fig. 4. This part may be formed separate, and attached to the head of the punch. The punch is pressed down by the lever C, when operated on by the cam F, and is raised by the spring D¹.

The cam-wheel F is supported by the standard E rising from the base, A. It has a double cam, as seen in fig. 1, and two pins, F² and F³, near its lower edge, for moving the slides, and to its face is attached the treadle-rod F¹.

Under F, and passing through the lower end of the standard B, is the slide G. It has a small friction-roller in its front end, g¹. A pin, g², at its side, serves to control its motion, and the pin g⁴ engages with the pins F² or F³, by means of which forward and back motion is given to the slide.

Lying on G is another slide, H. It has a slot through it, through which the pin g⁵ passes. The front end of the upper slide, when in place, is a little behind G, as seen in figs. 1 and 3. Attached to the frame is a spring, H², which catches into a notch in the side of H. This spring has a projection downwards, which rests in a tapering recess in the side of G. By means of the pin, slot, and spring mentioned, the upper slide may be held in place while the lower slide is being drawn back sufficiently far that the roller shall bend the points of the hook around the end of the slide H; and when this has been done, the tapering notch in the side of G, operating on the projecting point of the spring, throws it out of the notch H, and the pin g⁵, taking hold of H, both slides are drawn back together, as hereinafter is more particularly mentioned.

The hopper I has a slot across its lowest point. The edge on the side the hooks descend slopes downward, and at the back of the edge on the other side is a flange, as seen in fig. 5. Two ways, K and K', extend, the first one, K, from the sloping edge of the slot, and the other, K', from the other edge, each way being a continuation of said edges. The front way, K', is a little higher than the other. The hook clasps K', and slides down on it, while the other serves to keep it on the way, as is seen in fig. 5. The flange on the edge of the slot described serves to prevent hooks from falling out if they do not catch on the way K'. Just opposite the points where the recess in the head of the punch is when the punch is at rest, the way K' is cut away a sufficient space to allow the passage of the hook to the recess in the punch. Directly back of the hook, when in this position, is an arm, L, which is pressed forward towards the punch by the pin F³, and is drawn back by the spring L'. The hopper has an agitator in its lower end, over the said slot. It consists of a conical roller, with India rubber, hair, or the like, in strips projecting from its surface, by which to turn over such of the hooks as do not fall right in the ways at first. This agitator is made to turn slowly by means of the connecting-rod I², arm-ratchet and pawl I³, while on the back end are another ratchet and spring-catch, to prevent it from turning backwards.

The operation of the machine will be readily understood from the description given. Hooks are thrown into the hopper, some of which, at least, will find their way on to the ways, while the others will be unable to get out by reason of their form and the flange at the edge, and will be thrown up by the agitator until they also fall right. The agitation of the machine and their own gravity will cause them to descend to the lower end. If now the work to be operated on is held on the top of the slide H, and the cam-wheel pressed slightly backwards, the arm L, forced forward by the pin F³, will force the hook from the way through the opening in the outer one, and into the recess in the head of the punch D. If now the operator will press down the treadle, the punch will come down with such force as to carry the points of the hooks through the leather, into the notches in H, and between the roller and the end of G. By continuing the pressure on the treadle, the pin F³, engaging with the pin G⁴, will draw G back a short distance, the effect of which is to bend the points of the hooks around the end of H while in the notches therein. When this has been completed, the slide G has got so far that the tapering notch G² has operated on the spring H², and thrown it out of the notch in H, when both slides are drawn back together (H by means of the pin G⁵) sufficiently to allow the punch D to reach the base, when the second cam forces it down, and the hook is firmly clinched in the work. On raising the foot from the treadle, the cam will be drawn back by a spring or weight, which will force the slides G and H and the arm L forward, inserting another hook in the head of the punch to be operated.

Of course, the machine will operate without the hopper or ways, as the punch may be fed by hand; and there is a variety of ways in which the various movements may be given to the punch and slides.

I do not, therefore, wish to confine myself to the particular mode herein described, for my invention consists not only in the arrangement of parts, but in feeding automatically the hooks, and driving them through the leather, bending the points, and clinching them firmly by a single simple motion.

Instead of making the head of the punch as described, it may be made with a recess for the hook in the head, as seen in fig. 6, at N, with a strap, O, surrounding the head, turning on a pin, O¹, and held in place by the spring O², with a cam, O³, on its side, operated by the spring-arm O⁴, by means of which, in raising the punch, the strap is turned down so as to discharge the hook. When the spring O⁴ has passed the cam, the spring O² presses the strap back into its place. A stop, O⁵, on the under side of the arm B², will keep the strap in place while the hook is being pressed in. But I do not claim this form in this application.

Claims.

1. The slides G and H, constructed substantially as described.
2. The punch D, with recess for holding the hooks, constructed substantially as described, in combination with the said slides.
3. The arms L, pin F³, and spring L', constructed and operating in combination, substantially as described.
4. The cam F, lever C, and punch D, in combination, substantially as described.
5. The agitator, constructed and operating substantially as described.
6. The ways K K', constructed and operating substantially as described, in combination with the arms L.

LEWIS S. WISWELL.
